UNITED STATES PATENT OFFICE

JESSIE McCUTCHEON NELSON, OF NEW YORK, N. Y.

DESIGN FOR A TOY BANK

Application filed January 2, 1929. Serial No. 29,482. Term of patent 14 years.

To all whom it may concern:

Be it known that I, JESSIE McCUTCHEON NELSON, a citizen of the United States, residing at 955 Lexington Avenue, city, county, and State of New York, have invented a new, original, and ornamental Design for Toy Banks, of which the following is a specification, reference being had to the accompanying drawings, forming a part thereof.

Fig. 1 is a front elevational view showing my new design; and

Fig. 2 is a side elevational view illustrating my new design.

I claim:

The ornamental design for a toy bank substantially as shown.

JESSIE McCUTCHEON NELSON.
